DISPLAY SIGN

Job Hutchinson, Great Neck, N. Y., assignor to
Visual Merchandiser, Inc., New York, N. Y., a
corporation of New York

Application April 1, 1939, Serial No. 265,431

6 Claims.

(Cl. 40—84)

This invention relates to a display sign and has for an object to provide an improved construction over my copending application Serial No. 225,267.

5 Another object of the invention is to provide a display sign wherein a large number of sign members may be brought into view and then moved out of view in succession all from the same direction.

10 A further object of the invention is to provide a display sign wherein sign members may be brought to position in back of a window, the structure being such that it will function continuously as long as the power is turned on and the sign members will be successively brought opposite the window and held stationary for a given length of time and then moved out of the way.

An additional and more specific object is to provide a display sign which occupies comparatively small space and, at the same time, presents numerous independent sign members to view in succession, the structure being such that during the functioning of the sign the sign members will be brought in succession opposite a position to be viewed and then moved in a path out of sight until all the sign members have been exposed to view, after which the operation is repeated once or more times as desired.

20 Another object of the invention is to provide a display sign wherein sign members may be brought successively to view in back of a window and in front of illuminating devices, whereby the successive signs may be illuminated both while they are stationary in front of the window and as they are moving to that position and from that position.

In the accompanying drawings—

Fig. 1 is a sectional view through Fig. 4 approximately on the line 1—1, illustrating the mechanism in elevation and the casing in section;

40 Fig. 2 is a sectional view through Fig. 1 approximately on the line 2—2, certain parts being omitted from the view for the purpose of clearness;

45 Fig. 3 is a view similar to Fig. 2 but showing the parts in a different position;

Fig. 4 is a horizontal sectional view through Fig. 1 approximately on the line 4—4;

50 Fig. 5 is a sectional view on an enlarged scale of the lower part of the mechanism shown in Fig. 2 and illustrating all the detail parts in their relative positions;

55 Fig. 6 is a fragmentary perspective view of one end of a sign member or sheet together with the parts connected thereto;

Fig. 7 is a perspective view of one end of a carrier for the roll shown in Fig. 6;

Fig. 8 is a detail fragmentary perspective view of a block adapted to fit into the structure shown in Fig. 7, together with one end of the pulling bar 5 shown in Fig. 6;

Fig. 9 is a perspective view of one end of the plate adapted to be connected with the structure shown in Fig. 7 for holding the block of Fig. 8 in correct opposite position;

Fig. 10 is a fragmentary sectional view through Fig. 1 approximately on the line 10—10;

Fig. 11 is a fragmentary sectional view illustrating the sign moving chain and gearing associated therewith;

Fig. 12 is a view similar to Fig. 3 but showing a slightly modified construction.

Referring to the accompanying drawings by numerals, 1 indicates a casing of any desired kind, as for instance, metal. This casing is preferably rectangular and the parts secured together in any desired manner. At the front, however, the casing is provided with a window 2 which may be connected to the front wall 3, which front wall may be wood or other suitable material without departing from the spirit of the invention. Arranged interiorly of the casing 1 are supporting plates 4 and 5 which extend from the top to the bottom of the casing and which may be welded or otherwise rigidly secured to the casing. These supports are preferably metal, though they could be made of wood and if made of wood they may be secured in any suitable manner to the casing, as for instance by screws, brackets, or the like. The supporting plates 4 and 5 are adapted to carry or support all the mechanism except the motor 6 and associated parts, as shown in Fig. 1, which are supported on a platform 7 carried by brackets 8 secured to the bottom of the casing 1 in any desired manner. The motor 6 is preferably an electric motor and may be connected to a source of current in any desired manner. As shown in Fig. 1, a receptacle 9 is provided which is adapted to feed current not only to the motor but to lamps 10 as hereinafter fully described. Current passing through the receptacle 9 must pass through what may be termed a master switch 11 and from this switch the current flows to auxiliary switches 12 and 13. The auxiliary switch 12 controls the current to the lamps 10 while the auxiliary switch 13 controls the current to motor 6. If desired, a resistance 14 could be provided between the switch 13 and motor 6.

The motor 6 is connected through any suitable form of clutch 15 to a gear reducing struc- 55

ture 16 of any desired kind and this gear reducing structure has a driving shaft 17 extending therefrom on which the sprocket 18 is mounted and to which it is rigidly secured. As illustrated particularly in Fig. 10, the sprocket wheel 18 carries a chain 19 which passes over sprocket wheel 20. The sprocket wheel 20 is rigidly secured to shaft 21 so as to rotate shaft 21 and respective sprockets 22 secured thereto. As illustrated in Fig. 4, there are two sprockets 22 and these sprockets accommodate the respective chains 23 and 24, which chains pass over the respective sprocket wheels 25 adjacent the top of the machine. As illustrated particularly in Fig. 2, each of the sprocket chains 23 and 24 is provided with a special link 26 which is formed with a lug or abutment 27 in position to strike the respective blocks 28. As shown in Fig. 4, there are two blocks 28 and the parts are so set and proportioned that the lugs 27 on the respective chains will simultaneously strike the respective blocks for raising the same. Each of the blocks 28, as shown in Fig. 8, is provided with a notch 29 for accommodating the end of the stretching or pulling rod 30 and with an aperture or bore 31 for accommodating the end of a rod 32 connected to a roller 33. All the rollers 33 and associated parts are identical so that a description of one will apply to all.

The roller 33 is in the nature of an ordinary curtain roller but without pawls. As shown in Fig. 4, this roller is provided with a casing 34 connected with suitable end members 35. A coil spring 36 is arranged within the casing 34 and positioned to rotate casing 34 for a sign sheet 37 thereon when permitted to do so. The sign sheets or members 37 may be formed of paper, cloth, or other flexible material. On these flexible members are printed or otherwise mounted advertisements or any form of sign desired. Normally the parts are wound, as shown particularly at the right-hand part of Fig. 5 and also in Fig. 6.

As both sides of the mechanism interior of the supporting plates 4 and 5 are the same, a description of one side will apply to both. For the purpose of description, the assemblage indicated by the numeral 38 in Fig. 5 will be called a sign group. This group consists of rollers 33, sign sheet or member 37, spring 36, rod 32, block 28, fitting 39 as shown in Fig. 7, transverse bar 40, and retaining plate 41. The illustration in Figs. 6 to 9 is the same at both sides of the machine and the numerals in these figures are adapted to be used at both sides of the machine.

The fitting 39 is substantially U-shaped, as shown in Fig. 4, and in addition is provided with a cutout 42 into which block 28 fits. On the under portion 43, as shown in Fig. 7, there is secured by screws or other means, a bracket 44 which clamps the bar 40 rigidly in place. If desired, the bar 40 could be welded or otherwise secured to fitting 39. As illustrated in Fig. 1, suitable screws 45 hold the respective brackets 44 in place. Journal pins or screws 46 and 46' are screwed into the end 47 of bracket or fitting 39 and these screws carry the respective rollers 48 and 49. Rollers 48 and 49 travel in an endless path 50 (Fig. 4). The path 50 is formed by a channel iron 51 which, if desired, may be provided with a flange 52 bolted or otherwise rigidly secured to the supporting plate 5. As illustrated in Figs. 2, 3 and 6, the channel iron 51 has a pair of parallel sides and arc-shaped ends, one of the sides being positioned near the front wall 3. As illustrated in Figs. 2 and 5, there are a

large number of sign group 38 and all of these groups are constructed identically with the respective rollers 48 and 49 thereof fitting into the respective channel irons 51 and 51'. Referring again to the fitting 39, it is to be understood that when the block 28 is moved into the notch 42, the retaining plate 53 is secured to fitting 39 by suitable screws and, consequently, block 28 cannot move out of the fitting 39.

In case it should be desired at any time to change one of the sign sheets 37, the plate 53 adjacent the sign sheet is removed and then the respective blocks 28 are removed. The sign sheet is then removed and a new one provided, if desired, and then the other parts replaced.

The various sign groups have their rollers 48 and 49 positioned in the respective runways 50 and tend to automatically move downwardly by reason of gravity. However, means have been provided as hereinafter fully described whereby the various sign groups are held against movement by gravity until properly released, and this release merely releases one sign group at a time. As shown in Fig. 2, the flanges forming the respective runways 50 at the front are cut away. A friction plate 54 on each side of window 2 is provided and normally functions to hold the sign groups 38 in their lower position. Springs 66 and 67 carried by the the casing 1 act to force the respective friction plates 54 to the position shown in Fig. 2, whereby the curved end 68 at the bottom holds the sign group from rising and the lug 64 at the top holds the upper sign group from moving downwardly. At the rear of the casing the respective runways have their inner flanges 50' offset rearwardly to permit the respective friction plates 54 at the rear to press against the various rollers 48 and 49 to resist the tendency to move under the action of gravity. Springs 54' and 54'' are carried by flanges 50' and function to move the friction plates resiliently against the respective rollers 48 and 49. In this way the various sign groups are supported somewhat but not completely.

At the bottom of the runways 50, as shown in Fig. 2, there is provided a toothed member 55 having a number of teeth 56 spaced apart properly to readily straddle one roller from each of two adjacent sign groups. As illustrated in Fig. 2, the rollers 48 and 49 are in one sign group, while rollers 48a and 49a are in the next sign group. The toothed wheel 55 rotates as indicated by the arrow 57 so that as soon as the particular sign group 38' shown in Fig. 2 is moved upwardly from the position shown in Fig. 2 to that shown in Fig. 3, or farther upwardly, the next sign group 38'' will be immediately raised to the position formerly occupied by the sign group 38', as shown in Fig. 2. This raising movement is caused by the downward movement of the various sign groups held partly by the friction of rear plate 54. To help the friction plate 54 support the sign groups, the roller 49a will strike the tooth 56 of wheel 55 next to the left, as shown in Fig. 2, and will be prevented from further movement except as the toothed wheel 55 moves. This toothed wheel moves very slowly and in proper time to allow the successive sign groups to pass in order as the machine functions. Concerning the toothed wheel 55, it will be observed that the same is rigidly connected to a shaft 58 and, as shown in Figs. 4 and 11, shaft 58 is rigidly secured to a large gear wheel 59 which continually meshes with a small pinion 60 rigidly secured to a gear 61, which latter gear is continually in mesh.

with a small pinion 62 rigidly secured to shaft 21. It will be seen, therefore, that by reason of this train of gears and by reason of the fact that the shaft 21 is rigidly secured to the respective sprocket wheels 22, the respective chains 23 and 24 and the toothed wheel 55 will move in timed relation to each other. As shown in Fig. 2, the lug 27 is at its lowermost point and as the chain moves in the direction indicated by the arrow 63, lug 27 will strike against the block 28 of the sign group 38, as shown in Fig. 2, and begin to force the same upwardly. As shown in Fig. 3, the sign group 38' has been moved approximately half way up and as it moves upwardly the sign sheet or member 37 will be unwound, as shown in Fig. 5, so as to be exposed through the window 2.

When the parts are in the position shown in Fig. 3, the sign member below the sign group 38 will be seen and the sign member 37 above this group will also be seen. As the machine continues to function the sign group 38 will move not only to the position shown in Fig. 3 but will move upwardly to the upper position shown in Fig. 2. As the sign group approaches the upper position shown in Fig. 2, it will strike the protuberance 64 and move the friction plate 54 out of the way. The respective springs 66 and 67 acting on the plate 54 will move the lower end of the plate to the position shown in Fig. 2 as soon as the group 38' has moved to substantially the position shown in Fig. 3. Meanwhile the toothed wheel 55 will hold back the groups attempting to move past the wheel. Immediately after the turned-up end 68 has moved to the position shown in Fig. 2, the wheel 55 will move out of the way and then the following sign group will move upwardly and be stopped by the curved end 68. Meanwhile the sign group 38 continues to move until it snaps past the lug 67. In fact this sign group will continually move until the lug 27 passes the same.

As the shaft 21' is offset with respect to the path 50, the lug 27 will move the sign group a short distance above the position shown in Fig. 2 and then leave the same, whereupon the sign group will drop down to the position shown in Fig. 2 and rest against the lug 67. This dropping down is really caused by the tension of the spring 36 on the lower sign group. The sign member 37 displayed will remain stationary until the lug 27 passes around the sprocket wheel 23 and then downwardly and around sprocket wheel 22 for releasing another sign group. It will be seen, therefore, that there will be a stationary period for the sign sheet or member 37 which is approximately the same length as the time necessary to move the sign member into display position. It will be understood, of course, that the machine may be operated at various speeds as desired.

As illustrated in Figs. 2 and 5, there are provided bars or pins 69, 70, 71 and 72. The bars 69 and 70 are connected by plate 73 which is bent around the respective bars 69 and 70 and from bar 70 the plate forms a spring 74 for holding the sign member 37 against moving inwardly. The bars 71 and 72 likewise are provided with a sheet plate 75 merging into a spring 76 functioning in the same way as spring 74 except at a lower position. In back of the plates 73 and 75 there are provided reflectors 77 as shown in Fig. 5. These reflectors are arc-shaped and may be made of one piece of material or several pieces as desired. As shown in Fig. 5, they are made in one piece and bent to the desired shape so that the respective lamps 10, which are elongated electric

bulbs, may properly illuminate the sign sheet 37 and practically all the light be directed toward the sign sheet. Any suitable wiring may be provided to connect the various lamps 10 with the switch 12. It will be understood that the lamps 10 when in use are preferably continuously lit but, if desired, a flashing structure of any desired kind may be inserted in the circuit of these lamps to turn the same on and off automatically at spaced intervals.

Referring again to the shaft 21 and the sprocket wheels 22, it will be observed that these sprocket wheels and this shaft rotate continuously when the machine is functioning. From Figs. 4 and 5 it will be observed that there are provided a pair of rubber or other resilient rollers 78 and 79 rotatably mounted on the shaft 21. These rollers are prevented from longitudinal movement by suitable stops 80 which may be held in place by set screws or other suitable means. When a sign group 38 is moved to a position preparatory to being actuated by the lug 27, the sign group is checked in its movement by the end 68 of friction plate 54 and also by the bar 40 striking the respective rollers 78 and 79. However, when the lug 27 presses against the blocks 28 the resistance of the members just described will be overcome and the sign group will be raised as shown in Fig. 3 and, as heretofore described, the next sign group will be stopped by the turned up end 68 and by the respective rollers 78 and 79.

In Fig. 12 will be seen a modified structure to that illustrated in Figs. 2 and 3. The general layout is the same but the modification has to do with a toothed wheel 81 which is secured to shaft 58 and really takes the place of the rubber wheels 78 and 79. The toothed wheel 81 is arranged so that when the roller 82 is fitting into any of the notches 83 one of the teeth 84 will be resting against the wall 47 of fitting 39 so as to prevent the sign assemblage 38 from moving upwardly. When the lug 27 strikes the block 28 and moves the same upwardly the power is sufficient to move the toothed wheel 81 one notch. This will cause the roller 82 to swing to the right, as shown in Fig. 12. This roller is rotatably mounted on a lever 85 which is pivotally mounted at 86 on a suitable support so that the spring 87 acting on the runway 51 may tend to hold the roller 82 in one of the notches 83. In this form of the invention also the respective sign groups 38 are spaced farther apart. To accomplish this result, there are provided links 88 and 89 pivotally connected with the respective rollers 48 and 49 of the several sign groups. Each of these links is provided at its outer end with a roller 90 whereby the various sign groups are spaced apart the desired distance. The action of the chains 23 and 24 is the same as in the preferred form and the other parts are of the same structure as in the preferred form so that the same numerals are used.

In operation, when the parts for instance are in the position shown in Fig. 5, one of the sign sheets 37 will be exposed to view through the window 2. If the motor 6 is started the respective chains 23 and 24 will begin to rotate as heretofore described and in due time the respective lugs 27 will strike the respective blocks 28 and begin to raise the lowermost sign group 38 illustrated in Fig. 5. As the uppermost sign group 38 on the left of Fig. 5 is gradually raised the spring 36 in the upwardly moving sign group 38 will wind the sign sheet 37 as the rod 30 at the upper end will remain stationary. As shown 78

in Fig. 3, the sign group will be moved upwardly at the same rate that the respective chains 23 and 24 move. In a short time the sign group will reach the upper end of its travel and as it moves upwardly it will pull the sign sheet 37, as shown at the left in Fig. 5, so as to expose the same through window 2. By the time that the sign group 38 at the left of Fig. 5 reaches the top of its travel the sign sheet 37 will be fully exposed. As the sign group 38 reaches the upper end of its travel it will strike the lug 64 and pass on upwardly and partly around the curved end 50' to runway 50. The movement will continue until the lug 27 slips past whereupon all of the sign groups at the left of the curved upper end 50' will fall back to substantially the position shown in Fig. 3. The sign sheet 37' which is now in front of the window 2 will remain stationary though the chains 23 and 24 will continue to move at their regular rate of speed. The sign sheet will remain stationary until the lug 27 again engages a sign group at the lower end of the travel of the chains and starts to raise the new sign group upwardly. The new sign group functions as the one just described and this action continues as long as the machine is in operation, whereby the sign sheet 37 of each sign group will be successively brought to view in back of the window 2 and will remain stationary for a prescribed length of time. After all of the sign groups have been disclosed, the operation continues so that there will be a second disclosure, a third, and so on as the machine continues to function. Sometimes it is desired to have a less number of sign groups in the runways 50 and when this is the case the structure shown in Fig. 12 is used. However, the sign sheets of these groups will be brought to view and held stationary a predetermined time in a similar manner to the way these members are brought to view and held stationary as shown in Figs. 2 and 3.

A certain number of sign groups have been shown in the accompanying drawings but, if desired, the runways could be made longer or shorter and thereby more or less of these sign members could be used without departing from the spirit of the invention.

By reason of the construction shown, particularly in Figs. 6 to 9 inclusive, it will be readily seen that the sign sheets 37 could be removed whenever desired and new ones substituted so as to change the signs according to the wishes of the person paying for the same. In the substitution, a new sign group usually would be provided, but, if desired, the old sign sheet 37 could be torn from the roller and a new one applied. The inner end of the sign sheet 37 may be tacked or otherwise rigidly secured to the casing 34.

I claim:

1. A display sign including a casing having a window, a pair of facing guideways arranged in said casing, there being one guideway on each side of said window, a plurality of sign groups having their ends slidably mounted in said guideways, each of said sign groups including a drum, a sign sheet having one end secured to said drum, a spring for normally rotating the sign sheet on the drum, means connecting the opposite end of the sign sheet to the next preceding group, means adjacent said window for preventing said sign groups from moving opposite said window, said means including a plurality of loosely rotatable rubber rollers positioned to engage part of the re-

spective sign groups as they move to the lower end of said window, an endless chain for each of said guideways, each of said chains having a lug positioned to engage and force the respective sign groups past said rollers and also past said window whereby the sign sheets of the succeeding group will be displayed as the preceding sign group is moved by the lugs, and means for causing said chains to continually function while the sign is in use whereby the various sign groups will have 10 their sign sheets displayed in succession opposite said window.

2. A display sign including a casing having a window, a pair of guideways arranged within the casing, a plurality of sign groups carried by said guideways so that in part of their travel the sign groups will move past said window, a toothed member positioned so that its teeth will in succession act as abutments for preventing the sign groups from passing said window, spring-pressed 20 means for resiliently holding said toothed member against rotation, a pair of endless chains, a lug on each of said endless chains positioned to engage the sign groups in succession opposite said toothed wheel and move the sign groups past the 25 toothed wheel and also past the window, and power actuated means for moving said chains continually during the use of the display sign.

3. A display sign including a casing having a window, a pair of endless guideways arranged 30 in the casing and provided with straight sections opposite said window, a spring pressed guide arranged interiorly of the casing adjacent the window, a plurality of sign groups having their ends loosely positioned in said guideways, means for 35 engaging and successively moving said sign groups past said window, each of said sign groups including a drum, a sign sheet having one end secured to the drum, a spring for winding the sign sheet on the drum and means at the other 40 end of the sign sheet for connecting the same to the next preceding sign sheet whereby as the respective sign groups are moved past said window the sign sheets of the respective sign groups will be spread out in back of said window, and 45 spring means acting on the sign sheets for holding the same against said spring pressed guide whereby the sign sheets may be clearly seen through said window.

4. A display sign including a casing having a 50 window, a plurality of sign groups arranged in said casing, guideways for guiding said sign groups so that they may move past said window, each of said sign groups including a pair of end members, a pair of rollers on each end member, 55 said rollers extending into the respective guideways, a rigid bar connecting said end members, a drum rotatably mounted on said end members, a sign sheet having one end secured to a roller, a spring for winding the sign sheet on the 60 roller and a bar connected to the free end of the sign sheet, said bar being mounted in the next preceding sign group, means for moving said sign groups successively past said window, said means moving the sign groups at spaced intervals past said window, each sign group as it moves past the window pulling the sign sheet of the next succeeding group so as to unwind the same and bring the last mentioned sheet to a position in back of said window, and a pair of 65 resilient rollers positioned adjacent the lower end of said window and arranged to engage the respective bars on the respective sign groups for preventing the movement of the sign groups to a position opposite said window until positively 70 75

moved by the means for intermittently moving the sign groups past said window.

5. A display sign including a casing having a window, a pair of guideways arranged within 5 the casing, a plurality of sign groups carried by said guideways so that in part of their travel the sign groups will move past said window, said sign groups filling said guideways at the part opposite said window and at the bottom whereby 10 the weight of the sign groups at the part of the guideways opposite the window will continually tend to move the sign groups toward said window, a toothed member so positioned that its teeth will act in succession as abutments for preventing the sign groups from passing said window, spring-pressed means for resiliently holding 15 said toothed member against rotation, a pair of endless chains, a lug on each of said chains positioned to engage the sign groups in succession opposite said toothed member and move the sign 20

groups past said toothed member to a position to be exposed opposite said window and then to a position in said guideways opposite said window, and power actuated means for moving said chains continually during the use of the 5 display sign.

6. In a device as set forth in claim 2 characterized by having a pair of endless guideways formed with vertically disposed parallel front and back sections and arc-shaped top and bottom sections, 10 said sign groups being sufficiently numerous to completely fill said back sections and said bottom sections whereby the weight of the sign groups acting under gravity will continually urge the sign groups in said bottom sections to move 15 toward said front sections and thereby permit the use of a minimum motive force in causing the sign groups to function.

JOB HUTCHINSON.

20
